UNITED STATES PATENT OFFICE.

JOSEPH KIEREN, OF GILBERT, MINNESOTA.

SWITCH-CLUTCH.

1,109,425.

Specification of Letters Patent.

Patented Sept. 1, 1914.

Application filed April 11, 1912. Serial No. 689,972.

To all whom it may concern:

Be it known that I, JOSEPH KIEREN, citizen of the United States, residing at Gilbert, in the county of St. Louis and State of Minnesota, have invented certain new and useful Improvements in Switch-Clutches, of which the following is a specification.

This invention relates to locking mechanisms for switch stands whereby the switch stand may be locked to prevent the throwing of the switch by unauthorized persons.

A further object of the invention is to assemble the parts in such manner that it is practically impossible to break or disconnect the parts of the stand whereby the switch may be thrown by an unauthorized person.

A still further object of the invention is to provide, in combination with a switch stand mechanism, a lock of the special design and especially adapted to be used in combination with such a stand mechanism. This lock is provided with a bolt made up of 25 sections connected together with a comparatively weak pin and in case the lock should be removed from the stand by force, this bolt will break at its weakest point, whereby a portion of the bolt will remain in engagement with the stand and thus render it impossible to operate the switch.

For a full understanding of the invention and the merits thereof, reference is to be had to the following description and accompanying drawings, in which:

Figure 1 is a perspective view of the lock mechanism applied to a switch stand; Fig. 2 is a vertical sectional view of the same; Fig. 3 is a side elevation of the lock used upon the stand with parts removed and parts in section; Fig. 4 is a transverse section of the lock cut on the line 2—2 of Fig. 3; Fig. 5 is a side elevation of the lock similar to Fig. 3 but showing the positions of 45 the parts when the bolt is retracted; Fig. 6 is a sectional view of the lock cut on the line 4—4 of Fig. 5; Fig. 7 is a perspective view of a block and guides used in the lock showing the parts separated. Fig. 8 is a similar 50 view of the bolt of the lock and adjacent parts. Fig. 9 is a sectional view on the line 9—9 of Fig. 2.

Corresponding and like parts are referred

to in the following description and indicated in all the views of the accompanying drawings by the same reference characters.

As illustrated in the accompanying drawings, the switch mechanism includes a center bar or mast 1, which is square in transverse section and is of the usual form. This center bar or mast is operatively connected to the switch points (not shown) in any usual manner. The upper portion of the bar is square in cross section but the lower portion of the bar is circular in cross section. The square portion of the bar 1 is slidably received in a sleeve 2 which is provided with a central square passage for the center bar. When the sleeve 2 is properly positioned upon the center bar 1 it is secured thereto by set screws (not shown) or any other suitable securing devices, so that the sleeve cannot move independently of the bar. A lever 3 is fulcrumed upon the sleeve 2 in the usual manner and a collar 4 is slidably mounted upon the sleeve 2. Links 5 are pivotally connected with the lever 3 and the collar 4 and serve as means for moving the collar 4 along the sleeve 2 when the lever is swung. The collar 4 constitutes a principal part of the clutch mechanism and is provided at one side with a socket 6 which is adapted to snugly receive the face plate of the lock, hereinafter to be described. A perforation 7 passes through one side of the collar 4 and extends through the inner wall of the socket 6 to the inner wall of the said collar. A perforation 8 is provided in one side of the sleeve 2 and a depression 9 is provided in one side of the center bar 1. The perforations 7 and 8 and the depression 9 at times register with each other for the purpose of receiving a bolt as will be explained hereinafter.

The switch stand proper or base 15 is of any suitable or usual form and resting upon the upper end of the switch stand is a clutch member, 15^a having a circular opening through its center through which the central portion of the mast 1 passes. This clutch member 15^a has a square socket upon its upper face which receives the lower end of the sleeve 2 and also receives exterior to the sleeve 2 a downward prolongation 4^a of the collar 4. This downward extension 4^a is square in form so as to fit within the square

socket formed upon the upper face of the clutch member 15^a. Surrounding the downwardly extending central hub of the clutch member 15^a is a collar 15^b which is keyed to the central hub of the clutch member 15^a. A spring 15^c surrounds the mast 1 and is held at its lower end in any suitable manner while the upper end of the spring engages the collar 15^b. It will thus be seen that when the lever 3 or handle is raised after unlocking the collar 4 as will be hereafter described, the collar 4 will be drawn out of its clutching engagement with the clutch member 15^a and that, therefore, the collar 4, together, with the sleeve 2 and the mast 1, may be rotated by the handle when the handle is depressed, however, the collar 4 engages with the clutch member 15^a and the clutch member and the collar are thus interlocked with each other. The spring 15^c has a tension of about two thousand pounds and this spring will resist any attempt to rotate the mast 1 by hand while the collar 4 is depressed but will permit the rotation of the mast 1 by a passage of the train through the switch points.

In connection with the mechanism, a lock of special form is provided. This lock consists of an end plate 16 which fits snugly in the socket 6 provided at the side of the collar 4. A casing 17 is riveted or otherwise permanently secured to the plate 16 and a bolt 18 is slidably mounted in the plate 16. The inner portion of the bolt 18 is slotted as at 19 and receives a pin 20 which is mounted upon one of the sides of the casing 17. The collar is provided at the upper and lower edges of the socket 6 with outstanding lugs 21, and blocks 22 are inserted between the upper and lower lugs 21 and lie against the outer face of the plate 16. Pins 23 pass transversely through the lugs 21 and longitudinally through the blocks 22 and are spread at their ends so that they and the blocks cannot be removed from the collar 4 without using a chisel or similar implement. The inner portion of the bolt 18 is recessed at its lower edge as at 24 and this recess is adapted to be entered by the head of a key when the bolt is thrown. The bolt 18 is provided at its inner portion and at its upper edge with a shoulder 25. A tumbler 26 is pivotally mounted in the casing 17 and is provided with a lug 27 which normally engages the shoulder 25 upon the bolt 18 and holds the said bolt in projected position. A spring 28 is interposed between the upper portion of the tumbler 26 and the top side of the casing 17 and is under-tension with a tendency to hold the free end portion of the tumbler depressed so that the lug 27 lies in the path of movement of the shoulder 25. The free end portion of the tumbler 26 is located in the path of movement of a key which is adapted to be inserted through the

side of the lock and engage with a key pin 29 fixed to the side of the lock located opposite the key-hole opening in the casing.

A spring 31 is interposed between the end of the casing 17 and the inner end of the bolt and is under tension with a tendency to hold the outer end of the bolt projected away from the plate 16. The bolt 18 is adapted to be projected through the perforations 7 and 8 and into the depression 9 and center bar 1 when the parts are in locked positions, and while the bolt is in this position, it is impossible to move the collar 4 vertically along the sleeve 2.

A shoe 32 is mounted upon the pin 20 and is held in engagement with the upper edge of the inner portion of the bolt 18 by means of the tumbler 26 so that the bolt is held in proper alignment with the spring 31. The bolt 18 is made up of two pieces, indicated at 33 and 34. The innermost piece 33 is provided with a reduced threaded pin 35 which extends longitudinally through the piece 34. The pieces 33 and 34 are of the same external diameter so that the abutting ends of the said pieces fit snugly against each other. When the bolt is in projected position in the plate 16, the adjacent ends of the pieces 33 and 34 are substantially in the same plane as that face of the plate 16 which engages the inner wall of the socket 6. Therefore, should an unauthorized person attempt to break the lock by striking the same with a heavy implement, the bolt 18 would break at that point along the pin 35 where it joins with the broader part of the piece 33. This would leave the piece 34 and the pin 35 in the registering perforations 7 and 8 and the depression 9 and consequently, notwithstanding the fact that the body portion of the lock is removed from the clutch mechanism, the sleeve 2 could not be moved along the center bar 1 by the use of the lever 3 and therefore the switch to which the said center bar is connected could not be thrown.

The key may make a complete revolution and may be withdrawn from the casing 17, but as soon as the perforation 7 in the sleeve 4 is moved into alignment with the depression 9, the spring 31 will throw the bolt 18 into the said depression 9, whereby the sleeve 4 is held in fixed position upon the center bar 1.

A lug 36 is mounted upon the collar 4 and is provided with a perforation 37. The lever 3 is provided with a slot 38 which is adapted to receive the lug 36 when the free end portion of the said lever is swung down and the bail of a lock (not shown) may be passed through the perforation 37 so that the lever 3 is locked in a lowered position. The shoe 32 serves as a spacing block for that side portion of the casing 17 opposite the side thereof upon which the pin 20 is mounted and it also serves as a guide for the

shank of the bolt 18 and prevents the bolt from binding in the end of the casing 17 as it is moved longitudinally. The said block will also prevent the sides of the casing from being dented in and thereby destroying the efficiency of the lock.

The bolt 18 is provided at its inner part and at its upper edge with a shoulder 39. Guides 40 are secured in the casing 17 to 10 the upper side thereof, and a block 41 is slidably mounted between the said guides. This block is provided at its lower side with a downwardly disposed flange 42 which at times lies across the path of movement of 15 the shoulder 39, and at other times lies out of the path of movement of the said shoulder. A spring 43 is interposed between the block 41 and the side of the casing 17 and is under tension with a tendency to hold 20 the block 41 in such position between the guides 40 that the flange 42 will lie in the path of movement of the shoulder 39, and thus hold the bolt 18 in retracted position. The block 41 carries at one end a lug 44. 25 This lug projects through an opening provided in the side of the casing 17. When an operator moves the bolt 18 by the use of a key to retracted position, the tension of the spring 43 comes into play and the flange 30 42 carried by the block 41 is moved across the path of movement of the shoulder 39. This also projects the end of the lug 44 somewhat beyond the outer surface of the side of the casing 17. The operator may 35 then remove the key from the lock. When it is desired to lock the switch stand and the parts have been brought into register for this purpose, it is only necessary to move the block 41 back by pressing against the 40 end of the lug 44. This carries the flange 42 out of the path of movement of the shoulder 39, and under the tension of the spring 31 the bolt 18 is moved to protracted position 45 and the parts of the stand are locked together.

Having thus described the invention, what is claimed as new is:

1. In combination with a center bar provided with a depression and a sleeve having 50 a perforation, a locking mechanism comprising a collar mounted upon the sleeve, means for moving the collar, and a lock carried by the collar and having a bolt adapted to be projected through the perforation in the 55 collar into the depression.

2. In combination with a center bar having a depression, a sleeve slidably mounted thereon and provided with a perforation, a collar mounted upon the sleeve, and a lock 60 carried by the collar and having a bolt adapted to be projected through the perforation into the depression, said bolt having at a point between its ends a weakened place.

3. In combination with a bar provided 65 with a depression, a sleeve slidably mounted

upon the bar and having a perforation, a collar mounted upon the sleeve and having a socket, a lock having an end portion fitting snugly within the socket, and a bolt carried by the lock and adapted to be projected through the perforation in the sleeve 70 into the depression in the bar.

4. In combination with a bar having a depression, a sleeve slidably mounted upon the bar and having a perforation, a collar 75 mounted upon the sleeve and having a socket, a lock fitting at one end in the socket and carrying a bolt adapted to be projected through the perforation in the sleeve into the depression in the bar, and means carried 80 by the collar and lying over the end portion of the lock casing for securing the same.

5. In combination with a bar provided with a depression, a sleeve slidably mounted upon the bar and having a perforation, a 85 collar mounted upon the sleeve and having a socket with lugs located at the opposite sides thereof, a lock having a casing provided with an end plate which is snugly received within the socket, blocks interposed 90 between the lugs and lying against the outer face of said plate, and devices for securing the blocks to the lugs, said lock carrying a bolt adapted to be projected through the perforation in the sleeve into 95 the depression in the bar.

6. In combination with a bar having a depression, a sleeve slidably mounted upon the bar and having a perforation, a collar mounted upon the sleeve, a lock mounted 100 upon the collar and having a bolt adapted to be projected through the perforation in the sleeve into the depression in the bar, said bolt consisting of an inner piece having a reduced pin, and an outer piece which is seated upon the pin, the adjacent ends of the 105 said pieces fitting snugly against each other.

7. In a switch operating mechanism, a bar, a base in which the bar is journaled, a collar slidably mounted upon the bar, means 110 for sliding the collar, and locking means carried by the collar and engageable with the bar.

8. In a switch operating mechanism, a center bar, a collar slidably mounted thereon, means for sliding the collar, and locking means carried by the collar and having a bolt engageable with the bar, said bolt being weakened at a point between its ends. 115

9. In a switch operating mechanism, a bar, a collar slidably mounted thereon, a lock carried by the collar, and a bolt carried by the lock and engageable with the bar, said bolt being weakened at a point between its ends, the weakened point being 120 approximately at the edge of the casing of the lock when the bolt is in engagement with the bar. 125

10. In a switch operating mechanism, a bar, a collar slidably mounted upon the bar, 130

means for sliding the collar, said collar having a socket, a plate fitting snugly in the socket, a locking device carried by the plate and having a bolt engageable with the bar, and blocks permanently secured to the collar and fitting snugly against the outer surface of the plate at the sides of the locking device.

11. In a switch operating mechanism, a center bar, a collar slidably mounted thereon, means for sliding the collar, a locking means carried by the collar and having a bolt engageable with the bar, means for moving said bolt to protracted position, and means located in the lock and operable from the exterior thereof and independent of the bolt retracting means for holding the bolt in retracted position.

12. In a switch operating mechanism, a center bar, a collar slidably mounted thereon, means for sliding the collar, a lock carried by the collar and including a bolt,

resilient means for moving the bolt to protracted position, guides located in the lock, a block slidably mounted between the guides and carrying a part which projects from the side of the lock, and means for holding the block in the path of movement of the bolt to retain the bolt in retracted position.

13. In combination with a center bar, a sleeve arranged on said bar and having a perforation, a collar slidably mounted on said sleeve, means for moving the collar, and a lock carried by the collar and having a bolt adapted to extend through the collar and into the sleeve, said bolt having at a point between its ends a weakened place.

In testimony whereof I affix my signature in presence of two witnesses.
